FLUORESCENT LIGHTING FIXTURE

Donald F. Russell, Newburyport, Mass., assignor
to Sylvania Electric Products Inc., Salem,
Mass., a corporation of Massachusetts

Application September 12, 1947, Serial No. 141,357

Term of patent 14 years

(Cl. D48—4)

To all whom it may concern:

Be it known that I, Donald F. Russell, citizen of the United States, residing as Newburyport, in the county of Essex and State of Massachusetts, have invented a new, original, and ornamental Design for a Fluorescent Lighting Fixture, of which the following is a specification, reference being had to the accompanying drawing, forming part hereof.

The figure is a perspective view of a fluorescent lighting fixture, showing my new design.

The end opposite that shown is the same as the end shown. The back is plain and the top is open.

I claim:

The ornamental design for a fluorescent lighting fixture, as shown and described.

DONALD F. RUSSELL.
